UNITED STATES PATENT OFFICE

BYRON SPENCE, OF WAUWATOSA, WISCONSIN, ASSIGNOR TO CHR. HANSEN'S LABORATORY, INC., OF LITTLE FALLS, NEW YORK, A CORPORATION OF NEW YORK

SPIGOT

Application filed May 18, 1931. Serial No. 538,225.

The invention relates to spigots.

The general object of the invention is to provide a spigot that may be shipped with its container so that it may be built in or applied to the container at the time the same is filled with the contents to be dispensed and thus supply the consignee with a pouring device for the container that is immediately available for use. More particularly the spigot embodying the invention is designed so that it can be put on any keg or other suitable container without having to provide a special container and the pouring member is so constructed and arranged that when not in use it will be flat against the head of the keg and within the space between said head and the outer edge of the siding but when desired may be turned to a dispensing position in which the spout clears the outer edge of the siding.

A further object of the invention is to provide a spigot adapted for handling relatively heavy liquids such as rennet or viscous liquids and to obviate the necessity of specially venting the container the spigot is provided with a vent passage and means hereinafter described are also provided for keeping this vent passage in proper working condition.

The invention further consists in the several features hereinafter set forth and more particularly defined by claims at the conclusion hereof.

In the drawing, Fig. 1 is a vertical sectional view through a device embodying the invention, the section being taken on the line 1-1 of Fig. 2.

Fig. 2 is a detail plan view of a container with the spigot in dispensing position;

Fig. 3 is a detail sectional view taken on the line 3-3 of Fig. 1;

Fig. 4 is a detail elevation view of the pouring member showing one leg thereof;

Fig. 5 is a detail sectional view taken on the line 5-5 of Fig. 1.

In the drawing, the numeral 10 designates a container, here shown as a keg or barrel, having a head 11, siding 12 and chime ring 13, the head 11 being disposed below the extended outer edge 14 of the siding.

A casing member 15 is mounted in said

head and has a tapered plug portion 16, driven into one of the boards forming the head of the keg, and a shank portion 17, said member having concentric bores 18, 19 and 20 formed therein, the bore 20 being lined with a suitable sealing material, instanced here as a tube 21 of cork. This member 15 is formed of a material that will not be attacked by acid or brine present in rennet and is preferably either a molded composition 55 material such as a phenol-formaldehyde condensation material or a synthetic resin such as furfural resin composition. It is also to be noted that the axis of the concentric bores 18, 19 and 20 is disposed at an angle to the center of the plug portion 16 and is also eccentric to the axis or center of said plug portion.

A rotatable member 22 is in the form of an angled member having a tubular shank 70 portion 23, a cylindrical head portion 24 forming with said shank a shoulder 25, and an exposed spout portion 26 extending at an angle to said shank portion. The shank portion 23 is designed to fit within the bore 19 75 and have a snug fit in the tube 21 while the head 24 fits in the bore 18 and the shoulder 25 abuts against a shoulder formed between the bores 18 and 19. This pouring member 80 is also formed of molded composition material that will not be attacked by acid or brine and may be of the same material as those mentioned for the casing.

There are two angular passages formed in the pouring member 22, the main dispensing 85 passage 27 and the air inlet passage 28 and the branches of these passages have been given the same reference numerals. These passages as shown are open at the inner end of the shank portion 23 to facilitate manufacture but are sealed off by a cap member 29 which has a cylindrical plug portion 30 extending into the end 31 of the passage 27 and which is held in place by a screw 32 that passes through the cap and has threaded engagement with the lower threaded end 33 of the passage 28, the cap about these openings being flat and having sealing engagement 90 with the corresponding flat face 34 of the inner end of the shank portion 23. The outer 95 end of the shank portion 23 is provided with a 100

portion of the cap member also overlies the inner end of the shank portion 17 of the casing so that the pouring member is secured in operative assembled relation between the 5 shoulders of the pouring member and cap and the adjacent parts of the casing.

Alined passages 35 and 36 in the casing and tube 21 respectively communicate with the inner end of the passage 28 through a 10 port or passage 37 in the shank 23 when the pouring member is in a dispensing position.

Alined passages 38 and 39 in the casing and tube 21 respectively communicate with the inner end of the passage 27 through a port 15 or passage 40 in the shank 23 when the pouring member is in a dispensing position.

Turning the pouring member 22 from the dispensing position shown in the full lines in Fig. 2 to the closed position shown in dotted 20 lines in said Fig. 2 will obviously move the parts 37 and 40 out of registry with the ports or passages 35, 36 and 38, 39 so that the contents of the container will be prevented from flowing through the spigot. It will also be 25 noted that when the member 22 is in dispensing position its spout portion 26 projects at an angle to the head of the container and extends outwardly of the edge 14 of the siding so that the liquid will flow out of the 30 passage 27 clear of the container and that because of the angular disposition of the pouring member when the same is turned to a closed position said spout portion 26 will move down to a position against or adjacent 35 the head 11 and be disposed within the space formed between the head 11 and the outer edge 14 of the siding so that the kegs can be stacked without interference from the spigot.

It is also to be noted that when the spigot 40 is in dispensing position, air may enter the container through the passages 28, 37, 35 and 36 while the rennet or other liquid is flowing out of the container through the passages 38, 39, 40 and 27. However, it has been found 45 that under some conditions the air passage may tend to fill up as for example in case of a leak in the keg or in case of any pressure produced by the contents of the keg and if the liquid does clog this passage 28 there is 50 difficulty in starting the flow through the dispensing passage. To prevent these conditions interfering with the proper action of the device, I have provided a small hole or vent opening 41 to break any vacuum in the 55 air inlet passage and this it will be noted from Fig. 1 extends at an angle to that branch of the passage 28 in the spout position and in the direction of the flow of the material so that in case the liquid gets into the passage 60 28 tending to clog the same, it will readily drain out and in case the pressure within the container forces the contents out through this air passage when the spigot is turned to a dispensing position it will readily pass out 65 through the passage 28 in the spout portion

which is of larger diameter than the vent 41 and also that portion of the passage 28 in the shank portion.

It will also be observed that the pouring member 22 has the passage 27 formed in it 70 so that such passage is enclosed so that the liquid can only escape at the outer end of this passage and so that its flow is positively directed to the place where the operator wants it and there is no danger of its overflowing from the spout. Also the cork tube 21 effectively seals the pouring member from the escape of liquid when said member is turned to a closed position. 75

The cap member 29 is of the same material 80 as the casing and the screw 32 is of acid and brine resisting metal such as certain kinds of noncorrosive steel.

I desire it to be understood that this invention is not to be limited to any particular 85 form or arrangement of parts except in so far as such limitations are included in the claims.

What I claim as my invention is:

1. In a device of the character described, the combination with a container having a 90 head disposed below its outer edge, of a spigot mounted in said head adjacent said edge, said spigot including a casing secured in said head and an angled pouring member having a shank portion mounted in said casing to rotate on an axis at an angle to and eccentric 95 to the axis of said casing and having a spout portion provided with an enclosed dispensing passage, said pouring member having a closed position in which its spout portion is disposed below said outer edge and to permit ready 100 stacking during shipment and being rotatable to a dispensing position wherein its spout portion clears the outer edge of the container, said pouring member and said casing 105 having ports adapted to register with each other when said pouring member is in a dispensing position, the port in said pouring member communicating with said dispensing passage. 110

2. In a device of the character described, the combination of a casing for mounting in the head of a container, an angled pouring member having a shank portion mounted to rotate in said casing and an enclosed spout portion and having a dispensing passage, an air inlet passage and a vent for said air inlet passage, said pouring member having ports at the inner ends of said dispensing passage and said air inlet passage, said casing having 120 ports adapted to cooperate with said first named ports when said pouring member is in dispensing position, means forming a seal about the ported portion of said pouring member, and means for retaining said shank portion against removal from said casing. 125

3. In a device of the character described, the combination of a casing for mounting in the head of a container, an angled pouring member having a shank portion mounted to 130

rotate in said casing and an enclosed spout portion, said pouring member having a dispensing passage, an inlet passage and a vent for said air inlet passage extending at an angle thereto in the direction of outward flow, said pouring member having ports at the inner ends of said dispensing passage and said air inlet passage, said casing having ports adapted to cooperate with said first named ports when said pouring member is in a dispensing position, means forming a seal about the ported portion of said pouring member, and means for retaining said shank portion against removal from said casing.

15 4. In a device of the character described, the combination of a casing for mounting in the head of a container, an angled pouring member having a shank portion mounted to rotate in said casing and an enclosed spout portion, said pouring member having a dispensing passage and an air inlet passage, each of said passages being open at both ends, a cap secured to said shank portion to close off the inner ends of said passages and cooperating with said casing to maintain said shank portion in operative position, said casing and said pouring member having ports adapted to register with each other when said pouring member is in dispensing position, the ports in said pouring member respectively communicating with said dispensing and air inlet passages.

In testimony whereof, I affix my signature.
BYRON SPENCE.
